UNITED STATES PATENT OFFICE.

RALPH WALDO LANGWORTHY, OF TUCSON, AND HOMER HAMILTON SAVAGE, OF PHOENIX, ARIZONA.

CARRIAGE-RETURN ATTACHMENT FOR TYPE-WRITING MACHINES.

1,259,418.

Specification of Letters Patent. Patented Mar. 12, 1918.

Application filed July 6, 1917. Serial No. 179,014.

To all whom it may concern:

- Be it known that we, RALPH WALDO LANGWORTHY and HOMER HAMILTON SAVAGE, citizens of the United States, and residents of 5 Tucson, in the county of Pima and State of Arizona, and Phoenix, in the county of Maricopa, State of Arizona, have invented certain new and useful Improvements in Carriage-Return Attachments for Type-Writing Machines; and we do hereby declare the following to be a full, clear, and exact description of the invention, such as will enable others skilled in the art to which it appertains to make and use the same.
- 15 This invention relates to improvements in typewriting machines, and more particularly to means for returning the carriage, the object of the invention being to provide a simple and efficient mechanism which may be quickly and securely attached to the frame of a typewriting machine and which may be easily operated by the knee of the operator in effecting the return of the carriage.
- 20 25 With this and other objects in view the invention consists in certain features of construction and combinations of parts as hereinafter set forth and pointed out in the claims.
- 30 In the accompanying drawings; Figure 1 is a front elevation illustrating our improvements; Fig. 2 is an end view; Fig. 3 is an enlarged detail view of the toothed segment 17, and Fig. 4 is a similar view of the segment 20.
- 35 40 45 50 55 1 represents a portion of the frame of a typewriting machine, and at 2 a fragment of the paper feed mechanism of the machine is illustrated.
- Our improved carriage return mechanism is mounted in a frame 3, the base of which is extended and caused to project under one side of the frame of the machine, while one side or end of the frame 3 rests against the side of the frame of the machine. When in this position, the frame 3 of the carriage return mechanism is clamped to the frame of the machine as illustrated in Fig. 1. If desired, two clamps may be employed, and each comprises a clamping rod 5 hook-shaped at one end to engage the lower portion of the machine frame, and a lever 6 having a head 7 at one end pivoted to the frame 3 and receiving one end of the clamping rod.
- A grooved wheel 8 is located in the frame
- 3 and is provided with a shaft or arbor 9 mounted in two plates of said frame. An arm 10 is also attached to the frame 3 and projects therefrom in an inclined direction and is of such length that a pulley 11 carried by said arm near its free end, will be disposed approximately in horizontal alignment with the line space lever 12 on the carriage of the machine. A wire 13 (or other flexible device) is wound on and attached to the grooved wheel 8 and extends therefrom over the pulley 11 at one end of the arm 10, and at its other end, said wire is attached to the line space lever 12. The arm 10 may conveniently consist of a rod bent upon itself to form two parallel members pivotally connected with two of the plates of the frame 3. One of the frame plates may be provided with a plurality of holes 14, any one of which may receive a pin 15 on one of the members of the arm 10, whereby said arm may be held at any one of several adjustments and thus adapt the attachment to typewriting machines of different sizes and dimensions.
- The arbor 9 of the grooved wheel 8 carries a pinion 16 which receives motion from an internally toothed segment 17 secured to an arbor 18 mounted in the frame 3. The arbor 18 also carries a pinion 19 and motion is imparted to the same by means of a toothed segment 20 secured to a shaft 21 mounted in the lower portion of the framework. The shaft 21 is provided with a depending lever 22 which is preferably curved 85 or bowed somewhat as shown in Fig. 1, and is of such length and so positioned as to be disposed in proximity to the knee of the operator.
- It will be apparent that a limited side movement of the knee of the operator against the lever 22, will cause motion to be imparted through the gearing above described, to the grooved wheel 8, so that said wheel will be turned and cause the wire 13 90 to be wound thereon. This will cause sufficient pull on the wire to operate the line space lever and also return the carriage of the typewriting machine to its starting position.
- Our improvements may readily be applied to the frame of any typewriting machine having a carriage and may be easily operated with very little exertion on the part of the operator to return the carriage.

Having fully described our invention, what we claim as new and desire to secure by Letters-Patent, is:-

1. In a carriage return attachment for typewriting machines, the combination with a frame, adapted for attachment to a typewriting machine, a wheel mounted therein, a pinion carried by said wheel, a depending lever mounted in said frame, and gearing interposed between said lever and the pinion on said wheel, of an arm pivoted at one end to said frame and projecting laterally therefrom, a pulley mounted near the free end of said arm, a flexible device attached at one end to said wheel and passing over said pulley, the other end of said flexible device being adapted to be connected with the carriage of the machine, and means for adjustably securing said laterally projecting pivoted arm fixedly to said frame, whereby the attachment is adaptable to typewriting machines of different types and dimensions.

2. A carriage return attachment for typewriting machines, comprising a frame, a wheel mounted therein, an arm attached to said frame, a pulley carried by said arm, a flexible device for attachment to the carriage of the machine, said flexible device attached to the wheel and passing over said pulley, a pinion connected with said wheel, an arbor mounted in the frame, a segment carried by said arbor and meshing with said pinion, a pinion carried by said arbor, an operating shaft, a segment carried by said operating shaft and meshing with the last-mentioned pinion, and an operating lever carried by said operating shaft.

In testimony whereof, we have signed this specification in the presence of two subscribing witnesses.

RALPH WALDO LANGWORTHY.
HOMER HAMILTON SAVAGE.
